UNITED STATES PATENT OFFICE.

JOHN DEMAREST, OF NEW YORK, N. Y., ASSIGNOR TO THE J. L. MOTT IRON WORKS, OF SAME PLACE.

PULL-CUP FOR WATER-CLOSETS.

SPECIFICATION forming part of Letters Patent No. 274,182, dated March 20, 1883.

Application filed December 5, 1882. (No model.)

To all whom it may concern:

Be it known that I, JOHN DEMAREST, of the city and State of New York, have invented an Improvement in Pull-Cups for Water-Closets, of which the following is a specification.

Water-closets are usually incased with wood-work, and this wood-work varies in style, according to the views of the carpenter or architect. Sometimes the seat is flush with the wood-work surrounding the same. At other times the wood-work around the seat is raised so as to be flush with the lid that closes down over the seat. Sometimes the wood used is thicker than it is at other times. In almost all instances the pull or handle that operates the closet is at one side of the seat, and there is an opening through the wood-work for that pull, and usually there is a metal cup inserted in the wood-work, through which the pull is passed. It is important for the pull to work up and down freely and not bind or be drawn out of place. However, when the cup receives its support from the wood-work, the same is very often out of place in reference to the parts of the closet that are below and receive their support from the floor. To prevent the before-named difficulties the pull-cup has been fastened to a bridge at the upper end of the stand-pipe, as in my Patent No. 260,953; but this does not obviate the difficulty arising from variations in the thickness of the wood employed around the seat or from the use of differing styles of wood-work. Heretofore in many instances the carpenter called for pull-cups or pulls varying from those sent with the closets, so as to fit his wood-work.

The object of the present invention is to produce a compound pull-cap that is adapted to the different thicknesses or styles of wood-work, and one that will properly guide the pull and prevent the same becoming misplaced, so that the pull and cup may be fitted to any style of wood-work.

In the drawings, Figure 1 is a section representing a closet with my improved pull-cup applied thereto. Fig. 2 is a section in larger size, and Fig. 3 is a plan of the pull-cup.

The water-closet itself does not form any part of the present invention, and as the same may be of any suitable character I have not described the construction or mode of operation of the same.

The pull or handle *a* of the water-closet passes through the neck *b* of the pull-cup *c*, and this neck is fastened to the bridge *d* or other convenient portion of the water-closet itself. Around the pull-cup *c* is a cylindrical ring, *e*, with a top flange, *f*. The interior of this cylinder *e* fits the exterior of the pull-cup, so that when the proper hole or opening is sawed in the wood-work of the closet at the side of the seat the ring *e* is placed into that opening and around the cup *c*, with the top flange, *f*, resting on the top of the wood-work, and said ring is then secured in place. If the wood-work is thick, there will be a greater distance between the top edge of the cup *c* and the top of the flange *f*, and if said wood-work is thin the top edge of said cup will come almost up to the top of the cylinder *e*. In either position the cup will have a neat and finished appearance; but in one case the pull-cup will be deeper than in the other.

I claim as my invention—

The combination, with the water-closet pull, of a two-part pull-cup composed of the flanged ring *e* *f* and the cup *c*, substantially as set forth.

Signed by me this 29th day of November, A. D. 1882.

JOHN DEMAREST.
